FLUID FEED DEVICE

Eastman A. Weaver, Winchester, Mass., assignor,
by mesne assignments, to Stator Company, a
corporation of Massachusetts

Application December 7, 1946, Serial No. 714,799

6 Claims. (Cl. 230—1)

1

This invention relates to a self-regulating, continuous, heat-operated, fluid-feed device suitable for a wide variety of applications and, as illustrative of its utility, is herein shown as applied to an ejector-refrigeration apparatus of the type illustrated in United States Patent 2,174,301, granted September 26, 1939.

The principal object of the invention is to replace many of the complex, expensive, short-lived feed pumps now used by a single relatively inexpensive device subject to little wear and requiring no mechanical power supply. Other objects are to provide a hermetically sealed automatic boiler feed suitable for apparatus, such as refrigeration systems, using a permanent self-contained charge of fluid which must not leak away or be contaminated by atmospheric leakage; and to provide a boiler feed adapted to replace hand-controlled boiler feeds, such as injectors, by a self-regulating apparatus which will function only when needed. Further objects will be apparent from a consideration of the following description.

It is known that boiling gas-free liquids pass into the vapor phase not continuously, as in evaporation, but in a series of "bumps" caused by the fact that minute bubbles cannot form until substantial superheating of the liquid above its boiling point has occurred, at which time a sizable bubble appears, sometimes with such violence as to break a glass container. If the liquid be confined within an elongated chamber or tube in which a series of co-directed check valves are interspaced to define compartments at least partially filled with the boiling liquid, the bumping or sudden formation of each bubble tends to expel part of the fluid from its compartment and, due to the action of the check valves, the expulsion of the fluid is limited to one direction. By continuing the bumping action by applying the required degree of heat to the compartment, the intermittent oscillating pressure thus produced can be rectified to produce a flow of fluid even against a large pressure difference, if the number of units is adequate. The principle thus involved is to be distinguished from the action of a percolator which involves an air-lift principle working against little or no appreciable pressure head, and which does not depend upon intermittent generation of vapor from a superheated liquid.

The invention may advantageously be applied to absorption-refrigeration apparatus to feed an absorbent-refrigerant solution, or to ejector-refrigeration apparatus to feed a propellant fluid automatically into the boiler against a substan-

2

tial pressure, thereby permitting operation without mechanically-actuated valves or pumps which require power and usually involve more or less leakage to the atmosphere. This may be accomplished by including as a part of a boiler or generator a heated conduit comprising a series of codirected check valves constructed and arranged so as to define a plurality of spaced compartments each containing the boiling fluid. The conduit may communicate with the boiler proper or a manifold, except in certain cases where it may prove advantageous to make the entire boiler of these valve-spaced conduits arranged in series and/or in parallel, as for example in absorption refrigeration, where separation of fluids by distillation is involved and maintaining a pressure difference is essential.

Since such a device is actuated by individual bubbles, it works best with the boiler compartments quite small. Thus, its unique advantages are most apparent for small apparatus, although it is to be understood that the conduits may be combined in parallel to furnish an adequate flow required for large installations, as well as in series to furnish relatively high pressures.

In its simplified form, the device comprises a series of valve seats which are pressed, soldered, brazed, or otherwise secured at intervals within a vertical conduit, with a loose disk or the like valve member between each pair, the top surface of each valve seat and the bottom surface of each disk or valve member being smooth to insure tight closing. The other surfaces may be provided with teeth, projections, or other deformations to prevent closing in the wrong direction when a valve is lifted momentarily toward the seat next above it. Such an embodiment uses gravity to close the valves, although other means, such as springs, may be used; but in certain cases no valve closing means other than the pressure developed within the compartments may be found necessary, depending upon the particular conditions. The vertical arrangement for upward flow has the additional advantage of advancing the vapor preferentially as compared with the liquid, this being desirable, as the bumping is less effective when cushioned by the presence of much vapor in the compartment, and hence the vapor should be passed out of the units or compartments as rapidly as possible. However, other considerations may lead to the placing of these conduits horizontally or even for down flow in special cases.

55 Referring to the accompanying drawings which

illustrate the application of my device to a typical absorption-refrigeration apparatus:

Fig. 1 is a diagrammatic view of the system embodying the present invention;

Fig. 2 is an enlarged vertical section through the boiler-feeding apparatus; and

Figs. 3 and 4 are sections on the lines 3—3 and 4—4, respectively, of Fig. 2.

The system herein shown comprises a fire box or heating chamber C equipped with suitable heating means, such as a gas burner B, and within the chamber is a small boiler or vaporizer 1 which normally contains a body of suitable propellant, such as mercury. The lower end or bottom wall of the boiler is connected with a feeding device 2, constructed in accordance with the present invention, and the upper end or top of the boiler is connected with a riser 3 for conducting mercury vapor to an aspirator nozzle 4 from which the mercury vapor issues as a high velocity jet into a mixing chamber 5.

The mixing chamber 5 is connected by a vapor duct 6 to a cooler 7 which normally contains a body of liquid refrigerant, such as an aqueous solution of ethylene diamine. Refrigerant vapor is drawn from the cooler through the duct 6 and is entrained in the stream of mercury vapor passing through the mixing chamber 5. The resulting stream of mixed vapors is received by a funnel 8 which is provided with a cooling fin 19. The refrigerant vapor is compressed in this funnel while the propellant vapor (mercury) is condensed, the condensed propellant flowing into a drain pipe 12 connected to the lower end of the funnel, while the refrigerant vapor flows upwardly through a vapor duct 14 to the refrigerant condenser 15. The condensed refrigerant is received from the condenser 15 by a return pipe 16 having a trap 17 at its lower end which contains a small body of mercury. Refrigerant liquid piling up in the pipe 16 develops sufficient head so that some of the refrigerant may pass by the mercury into the trap and flow through a pipe 18 back to the cooler 7.

A trap 19 has one leg connected to the bottom of the cooler 7 and its other leg is connected with a downwardly inclined pipe 20. The trap 19 contains a body of mercury and the construction and arrangement of parts are such that when stray mercury is received from the cooler, the mercury may overflow the trap 19 into the pipe 20. The lower end of the drain 12 also communicates through a trap 21 with the lower end of the inclined pipe 20 which is connected to a return line 22. The pipe 22 is connected to a check valve 24 which in turn is connected to a return pipe 25 communicating with the lower end of the feeding device 2. The check valve 24, as shown in Figs. 2 and 4, comprises a cylindrical member having a frusto-conical shaped interior above which is a square or non-circular shaped disk 26 having a flat upper surface adapted to seat against the flat under-surface of the head or closure plate 28, in response to back pressure or fluid flow, thereby to permit flow of fluid only toward the feeding device 2, as indicated by the arrows in Fig. 2.

The feeding device or bumper feed 2 comprises an elongate vertically disposed cylindrical tube 30 having a closed lower end wall 31 to which the return pipe 25 is connected. Within the tube 30 is disposed a plurality of transversely extending partitions providing aligned check valves, each consisting of an inverted dish-shaped circular valve member 32 having a central opening

33 in its top wall and a side wall which is tapered or beveled as indicated at 34 adjacent to its junction with the top wall so as to define a chamber having a frusto-conical upper end, as shown in Figs. 2 and 3. A gravity-operated flat valve disk 35 of square or non-circular shape seats squarely on the upper face of each valve member 32 so as normally to close its associated valve opening 33. The valve members 32 thus define a series of spaced compartments, each having co-directed valves operative to permit fluid to pass upwardly in response to a pressure surge or wave, but opposing downward movement of the fluid. It will be observed that due to the non-circular shape of the valve disks 35 and the frusto-conical shape of the valve members 32, each valve disk is ineffective to close the valve opening just above it when forced from its seat. Hence, a surge or pressure wave created within any compartment is effective to seat the valve disk within that compartment firmly on its seat so as to prevent downward flow of fluid and at the same time raise or unseat the valve disk of the compartment next above.

25 The upper end of the feeding device 2 may be welded or otherwise suitably secured to the boiler 1, and both are disposed within the fire box C so that the feeding device is positioned to receive adequate heat from the burner B to effect the bumping action, it being understood that the burner B may be automatically controlled to supply fuel in accordance with the requirements of the system.

26 A summary of the operation of the system is as follows:

Assuming that the boiler 1, trap 21 and return line 22 contain the proper level of mercury, as indicated in Fig. 1, and that the cooler 7 contains the proper amount of liquid refrigerant, heat applied to the boiler 1 and feeding device 2 generates mercury vapor which passes through the tube 3 into the aspirator nozzle 4 from which the mercury vapor issues as a high velocity jet into the mixing chamber 5, thereby drawing refrigerant vapor through the duct 6, which is entrained with the stream of mercury vapor. Condensation of the mercury vapor takes place within the funnel 8, and the mercury condensate passes into the drain 12, through trap 21 into the return line 22, while the compressed refrigerating vapor passes through the condenser 15.

53 The mercury condensate flows through the check valve 24, as above explained, into the feeding device 2. Since the mercury within the vapor-generating compartments of the feeding device 2 is subjected to the main body of the flame issuing from the burner B, it is superheated sufficiently to effect the desired bumping action, and hence feeds the return fluid in the form of mercury vapor and entrained liquid mercury back into the boiler 1. When all the returned mercury in return-line 22 has been fed, the rate of pumping will of course diminish for lack of supply, and when the mercury contained in the feeding-device has been reduced sufficiently, feeding will cease until more return-mercury accumulates. The valves, however, continue to maintain the pressure-difference. Thus the feeding-device is self-regulatory, functioning only as there is liquid to be fed.

76 While I have shown and described one desirable embodiment of the invention, it is to be understood that this disclosure is for the purpose of illustration and that various changes and modifications may be made without depart-

ing from the spirit and scope of the invention as set forth in the appended claims.

I claim:

1. A heat-operated fluid-feeding device which comprises the combination of a heat generator and an enclosed chamber having an inlet and an outlet, and a plurality of co-directed check-valves defining a plurality of vapor-generating zones between an inlet and an outlet in heat transfer relation to said generator, said check-valves being effective to permit unidirectional fluid-flow from inlet to outlet and to prevent counter-flow.

2. A heat-operated fluid-feeding device which comprises the combination of a heat generator and an elongate member having an outlet at one end and an inlet at its opposite end, and a plurality of co-directed check valves within said member interspaced between said inlet and outlet and defining a plurality of vapor-generating zones in heat transfer relation to said generator, said check valves being effective to permit fluid flow only in a direction toward said outlet.

3. A heat-operated fluid-feeding device which comprises the combination of a heat generator and an elongate passage having an inlet at one end and an outlet at its other end, a plurality of spaced partitions extending across said passage and defining a plurality of vapor-generating compartments in heat transfer relation to said generator, each partition having a valve opening and a valve seat about said opening, and a normally closed valve member associated with each valve opening and arranged so as to permit fluid flow only in a direction toward said outlet.

4. A heat-operated fluid-feeding device which comprises the combination of a heat generator and an elongate vertically disposed channel having an inlet at its lower end and an outlet at its upper end, a plurality of vertically spaced partitions extending across the interior of said channel and defining a plurality of vapor-generating compartments in heat transfer relation to said generator, each partition having a valve opening and a valve seat extending about said opening, and a gravity operated valve disk disposed on each seat for normally closing the valve opening, the valve disks being arranged so as

to permit fluid flow only in a direction toward said outlet.

5. A heat-operated fluid-feeding device which comprises the combination of a heat generator and an elongate cylindrical tube having an inlet at one end and an outlet at its opposite end, a plurality of axially spaced partitions extending across said tube and defining a plurality of vapor-generating compartments in heat transfer relation to said generator, each partition having a valve opening and a valve seat extending about said opening, the wall of each partition facing the inlet end of said tube being of frusto-conical shape, and a normally closed valve disk of non-circular shape disposed against said seat, the valve disk being operative to permit fluid flow only in a direction toward said outlet.

6. A heat-operated fluid-feeding device which comprises the combination of a heat generator and an elongate vertically disposed cylindrical tube having an inlet at its lower end and an outlet at its upper end, a plurality of vertically spaced partitions extending across said tube and defining a plurality of vapor-generating compartments in heat transfer relation to said generator, each partition having a centrally disposed valve opening, the upper face of each partition defining a flat valve seat extending about said opening and the undersurface of each partition being of frusto-conical shape, and a gravity operated non-circular valve disk disposed on each seat, the valve disks being collectively operative to permit flow of fluid only in a direction toward said outlet.
